WRINGER AND WRINGER SUPPORT CONNECTION

Walter L. Kauffman, II, Erie, Pa., assignor to
Lovell Manufacturing Company, Erie, Pa., a
corporation of Pennsylvania

Application December 21, 1933, Serial No. 703,354

6 Claims. (Cl. 68—32)

The present invention is designed to improve the connection between a wringer and its support. Power wringers as ordinarily made are formed as a unit and secured to a wringer support, this support usually providing a means through which to transmit the power to the wringer. The wringer in use is subjected to very frequent strains which are carried into, or through the connection and which tend to loosen the connection between the wringer and its support. With the present invention a stile of the wringer is provided with projections which extend into sockets in the support, these projections and the walls of the socket taking a large part of the strain through the connection. Preferably the securing studs extend directly through the projection into the support, the heads of which are preferably housed within the projection. Features and details of the invention will appear from the specification and claims.

A preferred embodiment of the invention is illustrated in the accompanying drawing as follows:—

Fig. 1 shows a vertical section of an end of a wringer and a part of its support on the line 1—1 in Fig. 2.

Fig. 2 an end view of the wringer removed from its support and partly in section on the line 3—3 in Fig. 1.

Fig. 3 a front elevation of the wringer.

Fig. 4 a central section of a modification.

1 marks the base of the wringer frame, 2 the side stiles and 3 the top bar. These are ordinarily constructed of sheet metal, the side stile being usually of box form with slots 4 on their inner faces through which shafts 5 and 6 of wringer rolls 7 and 8 extend. Journal boxes 9 and 10 are arranged within the stile, the upper journal box being slidably supported therein and subject to pressure from the usual pressure spring 11.

The power shaft of the wringer is coupled ordinarily with a shaft 12 extending through a support 13. The support is provided with sockets 14 on the face next the wringer stile and the wringer stile is provided with projections 15 which extend into these sockets. These projections are preferably formed by striking them up in the sheet metal forming the outer side wall of the box-shaped stile. Studs 16 extend through openings 17 extending through the walls of the projection and these studs extend into screw-threaded openings 18 in the support 13. Heads 19 of the studs are housed within recesses 20 formed at the rear of the projections. It will be noted

that the openings 17 and in consequence the heads of the studs are directly opposite the slot 4 so that the studs may be readily put in place through this slot and the studs set up by tools extended through the slot.

Preferably there is little clearance between the end of the projection and the bottom of the recess and a slight clearance between the face of the support and the wall of the stile and the walls of the projections and recesses are slightly conical so that as the studs are set up there is a pressed engagement between the walls of the stud and the walls of the recess which forms a very rigid and secure connection between the support and the wringer. The slight resiliency of the metal forming the rear stile as it is drawn up tends to maintain the rigidity of the connection in use.

With this construction the connecting studs, or bolts, are entirely sealed so that the supporting walls of the wringer support may be entirely free from obstructions thus making it easier to fabricate and to plate, or polish, and also permitting of a more attractive structure and one more readily kept clean.

In Fig. 4 I have shown a modification in which an outer wall 2a of the stile is provided with a slight indentation 21 which has an opening through it. A cup-shaped fitting 22 is arranged in the opening in the indentation 21 and this is provided with a flange 22a which is arranged in the recess formed by the indentation. The fitting has an opening 23 which is adapted to receive a stud 24 for securing the wringer to a support. The stud head 25 is housed in a recess 26 formed by the fitting.

What I claim as new is:—

1. A wringer frame comprising a side stile of box form having a shaft receiving slot on its inner side and a projection on the outer wall of the stile opposite the slot, said projection being adapted to engage a recess in a wringer support and having an opening for receiving a securing stud.

2. A wringer frame comprising a side stile of box formation having a wringer shaft slot in its inner wall and a plurality of projections in its outer wall opposite the slot, said projection being adapted to engage sockets in a wringer support and having openings therethrough adapted to receive securing studs.

3. A wringer comprising a side stile of box form having formed on the outer wall thereof a member of a projection and socket connection for a support, the inner wall of the stile being slotted and the outer wall having a screw-receiving open-

ing opposite the slot in close relation to the member.

4. In a wringer, the combination of a stile of box form having a projection on the outer wall with a perforation through the projection and a recess within the stile at the rear of the projection; a wringer support having a recess receiving the projection and a screw-threaded opening in alinement with the opening through the recess, the peripheral walls of the projection and recess being included and in direct wedging contact; and a screw extending through the opening in the projection into the screw-threaded opening in the support and having its head housed in the recess, said screw being operable through the inner wall of the stile.

5. In a wringer, the combination of a stile of box form in cross section having an opening in its inner wall, a wringer support, said stile and

wringer support having between them recess and projection securing members having included peripheral walls in direct wedging contact and a screw extending through the projection and walls of the recess and drawing said peripheral walls into engagement, said screw being opposite the opening in the inner wall of the stile and operable through said opening.

6. In a wringer, the combination of a frame, comprising a stile of box form having an outer wall formed therein and a projection adapted to engage a socket in a wringer support, said projection having an opening therethrough adapted to receive a securing screw, the rear of the projection being recessed and adapted to house the head of the screw; and a wringer shaft bearing slidingly mounted in the stile and movable past the projection.
